UNITED STATES PATENT OFFICE

WILLIAM U. SNYDER, OF GLEN ELDER, KANSAS.

DESIGN FOR A WATERING-TROUGH.

SPECIFICATION forming part of Design No. 31,286, dated July 25, 1899.

Application filed June 29, 1899. Serial No. 722,346. Term of patent 7 years.

To all whom it may concern:

Be it known that I, WILLIAM U. SNYDER, a citizen of the United States, residing at Glen Elder, in the county of Mitchell and State of Kansas, have invented and produced a new and original Design for Watering-Troughs; and I do hereby declare the following to be a full, clear, and exact description of the invention, such as will enable others skilled in the art to which it appertains to make and use the same.

In the drawings, Figure 1 is a front view of the watering-trough. Fig. 2 is a longitudinal section taken on the line $x-x$ in Fig. 1. Fig. 3 is a plan view of the watering-trough. Fig. 4 is a cross-section taken on the line $y-y$ in Fig. 2.

As shown in the drawings, the leading or material feature of the design consists of a reservoir having a flat side, a head closing one end of the reservoir, a head arranged at a little distance inward from the other end of the reservoir, leaving an opening adjacent to the flat side of the reservoir, and a lip projecting from one end of the flat side of the reservoir in front of the said opening and forming a shallow chamber outside the last said head and within the body of the reservoir.

A is the reservoir, which is a portion of a cylinder, and a' is its flat side.

B is the head which closes one end of the reservoir.

C is the head arranged at a little distance inward from the other end of the reservoir,

and c is the opening formed between the head C and the flat side a' of the reservoir.

D is a lip projecting from one end of the flat side a' in front of the opening c and forming a shallow open-topped chamber d outside 40 the head C and within the body of the reservoir.

E are auxiliary shallow chambers which extend longitudinally along the reservoir, one on each side of the flat side a' , and which 45 communicate with the chamber d .

F are perforated lugs for the attachment of a bail or bucket-handle, projecting from the reservoir in front of the head C and one on each side thereof.

The device is used for watering poultry. It is filled by standing it on its head B and pouring water onto the head C, and it may then be carried about by an ordinary bail or bucket-handle.

When in use, the reservoir is stood upon its flat side a' , and the water flows through the opening c and stands at a constant level in the shallow chambers, which are automatically replenished from the reservoir.

I claim—

The design for a watering-trough, substantially as herein shown and described.

In testimony whereof I affix my signature in presence of two witnesses.

WILLIAM U. SNYDER.
